UNITED STATES PATENT OFFICE

164,491

TELEPHONE RECORDING PICKUP

Ernest E. Hansen, Jr., Glendale, and Lawrence M. Heineman, Los Angeles, Calif., assignors to Permoflux Corporation, Chicago, Ill., a corporation of Illinois

Application February 21, 1951, Serial No. 14,290

Term of patent 14 years

(Cl. D26—14)

To all whom it may concern:

Be it known that we, Ernest E. Hansen, Jr., and Lawrence M. Heineman, citizens of the United States, residing respectively at Glendale and Los Angeles, in the county of Los Angeles and State of California, have invented a new, original, and ornamental Design for a Telephone Recording Pickup, of which the following is a specification, reference being made to the accompanying drawings, forming a part hereof.

In the drawings:

Fig. 1 is a perspective view showing a telephone recording pickup embodying our novel design with the recording pickup in its normal position of use on a telephone receiver which is shown in broken lines for purposes of illustration;

Fig. 2 is a sectional view of the recording pickup taken along the line 2—2 of Fig. 1;

Fig. 3 is a front elevational view of the telephone recording pickup;

Fig. 4 is a side elevational view thereof;

Fig. 5 is a rear elevational view thereof;

Fig. 6 is a top plan view; and
Fig. 7 is a bottom plan view.

We claim:

The ornamental design for a telephone recording pickup, substantially as shown and described.

ERNEST E. HANSEN, JR.
LAWRENCE M. HEINEMAN.
